UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

BOILER-TUBE CLEANER.

1,184,544.

Specification of Letters Patent.

Patented May 23, 1916.

Application filed November 17, 1915. Serial No. 62,014.

To all whom it may concern:

Be it known that I, FREDERICK W. LINAKER, a subject of the King of England, residing at Dubois, in the county of Clearfield and State of Pennsylvania, have invented certain new and useful Improvements in Boiler-Tube Cleaners, of which the following is a specification.

This invention relates to certain new and useful improvements in boiler tube cleaners.

The present invention is more particularly adapted for boilers including banks of tubes that have associated therewith baffles that are arranged adjacent the tubes with the cleaning fluid distributing pipe for the tubes arranged adjacent the free end of the baffle. The cleaning fluid distributing pipe that is arranged adjacent the outer end of the baffle positioned against the bank of tubes in the chamber adjacent the fire box where the heat in the gases and products of combustion is the most intense, is subjected to a continued heat from the fire box and soon becomes burnt or otherwise injured unless some protecting means such as a shield is provided therefor.

The present invention therefore aims to overcome this difficulty and provides a protecting device for the distributing pipe and nozzles that is associated with the first bank of tubes that will completely shield the same when in inoperative position. The device as shown is applied to a boiler that is known in the trade as the Stirling type and includes semi-vertical and vertical banks of tubes but it is to be understood that the invention may as well be applied to horizontal water tube boilers without in any manner affecting the gist of the present invention.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is a cross-sectional view of a Stirling boiler with the present invention in operative position therein. Fig. 2 is a rear elevational view of a portion of the boiler tubes or flues with the distributing pipe associated there-

with, and illustrating the method of mounting the cleaning fluid distributing nozzles on the distributing pipe. Fig. 3 is a top plan view of a portion of the boiler tubes as illustrated in Fig. 2, illustrating the method of mounting the cleaning fluid distributing pipe. Fig. 4 is a detail sectional view of the distributing pipe, and a portion of an adjacent boiler tube as shown in Fig. 1, but arranged perpendicularly and illustrating the manner of mounting the cleaning fluid distributing nozzles in the distributing pipe and also the protective means for the pipe and nozzle, and, Fig. 5 is a detail perspective view of one of the bearing supports for the distributing pipe.

In boilers of this type where the gases and products of combustion primarily contact the water tubes or flues there is deposited on the tubes a coat of soot that is extremely difficult to remove unless the tubes are cleaned at short intervals of time. The cleaning fluid distributing pipe for removing this soot is positioned adjacent the boiler tubes at the outer end of the baffle and is preferably of the rotary or oscillating type and as is usual, the same is journaled at its ends in the sides of the boiler setting. Supporting bearing blocks for the distributing pipe are associated with the pipe and certain ones of the upper row of tubes and by which the distributing pipe is further supported. The distributing nozzles are carried by the pipe and are positioned to be moved to spaces between the adjacent tubes and in their inoperative position are completely removed from the heat zone of the furnace while heat refractory material is associated with the supports or nozzles which will prevent the intense heat from the fire contacting the distributing pipe, and means is also associated with the bearing blocks for further protecting the distributing pipe from the heat.

Referring more in detail to the accompanying drawings and particularly to Fig. 1, there is shown a boiler including the setting 10 having positioned therein banks of tubes A, B and C, and associated with the banks of tubes A and B, are baffles D and E. Cleaning fluid distributing pipes 11 are associated with the banks of tubes B and C and may be of any well-known construction in this particular art, but preferably being of the rotary type including operating 110

chains 12 as is indicated in dotted lines in Fig. 1. The piping system for feeding the cleaning fluid agent is diagrammatically shown in Fig. 1 and includes the main supply pipe 13 communicating with the feed pipe 13' which in turn communicates with the branch pipes 14 and each pipe is provided with valve control mechanism, while the main supply pipe 13 is provided with a drain cock as is indicated.

The present invention has particular reference to the cleaning fluid distributing pipe 15 that is arranged adjacent the bank of tubes A and the outer end of the baffle D, this pipe passing through the boiler and being journaled at its ends in the sides thereof which is of the usual construction of rotary or oscillating distributing pipe. As shown more clearly in Figs. 2 and 5, the distributing pipe 15 is further supported intermediate its ends by the bearing blocks 16, the inner ends of which abut the outer end of the baffle D while the bottom faces thereof are longitudinally grooved as at 17 for the purpose of being mounted on the upper row of tubes 18 of the bank A. The back or rear faces of the bearing blocks 16 are each provided with strap bearings 19 through which the distributing pipe 15 extends, it being noted that the bearing blocks are relatively immovable with respect to the baffle D and tubes 16 while the distributing pipe is permitted to freely revolve therein. These bearing blocks will prevent the gases and products of combustion from short circuiting or passing over the distributing pipe, and in order to insure the direct travel of the gases, the outer ends of the bearing blocks 16 are provided with tongues or lug extensions 20 that further protect the pipe from the intense heat in the products of combustion.

Any form and number of nozzles may be associated with the distributing pipe 15 and one of preferred construction is shown in detail in Fig. 4 and includes a nipple 21 threaded into the pipe 15 and carries a jet nozzle 22. The sections of the pipe that span the spaces between the boiler tubes 18 are provided with housings or shields including hub portions 23 mounted on the pipe and adjustably fixed thereto in any suitable manner, as by set screws 24. The shields are formed of channel-shaped members including side flanges 25 radiating from the hub 23 while end closure walls 26 are provided for the side flanges 25 at suitable points to provide a clearance space for the nozzle 22. The set screw holds the shield relatively immovable with respect to the pipe 15 while the nipple 21 is also threaded through the hub portion 23 which will further prevent relative movement of the shield and distributing pipe. The shields may be made of any suitable material as of cast iron or steel

while the side flanges constitute the channel member for the reception of a heat refractory material 27 to protect the same and also the distributing pipe, this refractory material being of plastic cement that is adapted to solidify or may be of any other suitable material especially adapted for this purpose. When the distributing pipe is inoperative position as shown in Figs. 2 and 4, the jet nozzle and distributing pipe are completely removed from the heat zone of the furnace and in such position the heat refractory filling 27 is positioned to face the boiler tubes and the heat zone and to form a continuation of the baffle D. Side flanges 28 of circular form co-incident to the curvature of the shields are carried by the outer side faces of the flanges 27 and are adapted further to prevent the escape of the gases and products of combustion from between the tubes and effectually prevent the same from contacting the distributing pipe at any point.

By reference to Figs. 2 and 4, it will be readily seen that the cleaning fluid distributing pipe in inoperative position is completely removed from the heat zone of the furnace and that the bearing blocks carrying the lug projections and the shields for the distributing nozzles effectively shield the pipe at the point where the same crosses the tubes so as to eliminate the danger of overheating the same which would be present without some means for protecting the pipe.

When it is desired to clean the tubes, the operating chains 12 causes the distributing pipe 15 to be revolved in the bearing blocks 16 and at which time the housings for the nozzles are also revolved with the distributing pipe to bring the nozzles into position adjacent the tubes, and at this time the refractory filling 27 for the housing members is moved to a position spaced from the tubes so that the distributing nozzles 22 are exposed and the jets of cleaning fluid issuing therefrom pass over the tubes to remove the coatings of soot therefrom. This cleaning operation consumes only a small amount of time and the cooling effect of the cleaning fluid agent will off-set the intense heat of the heat zone. After the pipes have been thoroughly cleaned, the operating chains cause the distributing pipe to be revolved in a reverse direction to remove the distributing nozzles from the heat zone and into the position shown in Fig. 4 to bring again the distributing nozzles to the positions remote from the heat zone and cause the refractory filling for the shields to be again exposed for protection of the pipe and nozzles as indicated. In this position, the refractory material 27 in the several shield members forms a continuation of the outer end of the baffle D and in combination with the bearing

blocks 16 and lug projections 20 carried thereby, the gases and products of combustion will be entirely remote from the distributing pipe and nozzles, whereby the same will be effectively protected from the intense heat in the heat zone.

While the present form of construction is preferred, it is to be understood that the device may as well be applied to boilers of other constructions without departing from the spirit and scope of the invention as set forth in the subject-matter claimed.

What I claim as new is:—

1. A tube cleaner comprising a rotatably mounted fluid distributing pipe, heat deflecting shields fixed to the pipe and movable therewith, and stationary shields constituting supports for the pipe and adapted to protect the same from heat when the pipe is in operative position.
2. A cleaner for the tubes of water tube boilers having a baffle arranged adjacent the tubes comprising a cleaning fluid distributing pipe arranged adjacent the tubes and outer end of the baffle, and means associated with said pipe adapted to protect the same from heat when the pipe is in inoperative position, some of said means being stationary and constituting supports for the pipe and the remainder being fixed to the pipe and movable therewith.
3. A cleaner for boiler tubes including a cleaning fluid distributing pipe, heat protecting stationary journal bearings for the pipe supported on the tubes, and means associated with said pipe and movable therewith adapted to protect the same from heat at the spaces between the tubes when the pipe is in inoperative position.
4. A cleaner for the tubes of water tube boilers having a baffle arranged adjacent the tubes comprising a cleaning fluid distributing pipe arranged adjacent the outer end of the baffle, journal bearing supports for the pipe mounted on the tubes, nozzles carried by the pipe adapted to be moved to exposed operative position adjacent the water tubes, and means associated with said pipe and nozzles and disposed between the pipe supports adapted to protect the same from heat when the pipe is in inoperative position.
5. A cleaner for boiler tubes including a cleaning fluid distributing pipe, journal bearing supports for the pipe, heat deflecting means for the pipe carried by the supports, and heat protecting means for the portions of the pipe extending across the tube spaces.
6. A cleaner for boiler tubes including a rotatably mounted cleaning fluid distributing pipe, and a plurality of heat deflecting devices for the pipe, some of which are stationary for supporting the pipe and others of which are movable.
7. A cleaner for boiler tubes including a rotatably mounted cleaning fluid distribut-

ing pipe, bearing blocks mounted on the tubes, straps carried by the blocks constituting journal bearings for the pipe, and shields carried by the pipe intermediate the blocks and movable with the pipe.

8. A cleaner for boiler tubes including a rotatably mounted cleaning fluid distributing pipe, stationary journal bearings therefor, said bearings constituting heat deflecting means for the pipe, shields carried by the pipe intermediate the bearings, and a refractory material filling for the shields adapted to be exposed to the heat zone when the pipe is in inoperative position.

9. A cleaner for boiler tubes including a cleaning fluid distributing pipe, journal bearing supports for the pipe associated with the tubes and pipe and immovable relative to the tubes, jet nozzles carried by the pipe, shields for the nozzles carried by the pipe spanning the space between the tubes and movable with the pipe, and heat-refractory material carried by the shields adapted to be exposed to the heat zone when the pipe is in inoperative position to protect the pipe and nozzles from heat.

10. A device of the class described including boiler tubes and a baffle arranged adjacent the same, a cleaning fluid distributing pipe rotatably mounted adjacent the outer end of the baffle, bearing blocks constituting journal supports for the pipe, means carried by said blocks adapted to deflect the heat from said pipe, the said blocks being immovable relative to the tubes and baffle, and shields carried by said pipe between the bearing blocks adapted to protect the pipe when in inoperative position and form a continuation of the baffle.

11. A cleaner for boiler tubes including a rotatably mounted cleaning fluid distributing pipe, distributing nozzles carried by the pipe, shields for the pipe and nozzles carried by the pipe adapted to lie in exposed position with respect to the heat zone when the pipe is in inoperative position, and means carried by the shields adapted to prevent the gases and products of combustion contacting the distributing pipe when the pipe is in inoperative position.

12. A cleaner for boiler tubes including a rotatably-mounted distributing pipe, shields carried thereby and movable therewith, the said shields including a filling of heat refractory material exposed to the heat zone when the pipe is in inoperative position, the said shields being movable with the pipe and adapted to expose portions of the distributing pipe and nozzles when the pipe is in operative position.

13. A cleaner for boiler tubes including a rotatably mounted distributing pipe, stationary supporting means for the distributing pipe constituting heat protecting means therefor, and means carried by the distribut-

ing pipe movable into spaces between the boiler tubes constituting heat protecting means for the pipe at the portions spanning the tubes when the pipe is in inoperative position.

14. A cleaner for boiler tubes including tubes and a baffle arranged adjacent the same, a cleaning fluid distributing pipe arranged adjacent the tubes and outer end 10 of the baffle, and heating protecting means for the pipe carried thereby and movable therewith, the said means being positioned, when the pipe is in inoperative position, to cause the gases and products of combustion 15 to travel beyond the outer end of the baffle and in a course remote from the pipe.

15. A cleaner for boiler tubes including tubes and a baffle arranged adjacent the same, a cleaning fluid distributing pipe arranged adjacent the tubes and outer end of 20 the baffle, means for supporting the pipe immovably associated with the tubes and forming a continuation of the baffle, and heat protecting means for the pipe arranged

between the pipe supports and forming a 25 continuation of the baffle when the pipe is inoperatively positioned.

16. A heat protector for distributing pipes comprising channel members fixed to the pipes and movable therewith, and exposed 30 heat refractory material filling for the channel members.

17. Means for supporting and protecting distributing pipes including blocks having journal bearing supports for the pipes, and 35 means for deflecting the heat from the pipes carried by the blocks.

18. Means for supporting and protecting a distributing pipe including journal bearing blocks in which the pipe is mounted, 40 and extensions carried by the blocks for causing the gases and products of combustion to travel in a course remote from the pipe.

In testimony whereof I affix my signature.

FREDERICK W. LINAKER.
